UNITED STATES PATENT OFFICE

170,630

TEXTILE FABRIC OR SIMILAR ARTICLE

Nathan Feinstein, New York, N. Y.

Application June 25, 1953, Serial No. 25,657

Term of patent 3½ years

(Cl. D92—1)

To all whom it may concern:

Be it known that I, Nathan Feinstein, a citizen of the United States, residing in the city of New York, in the county of Queens, and State of New York, have invented a new, original, and ornamental Design for a Textile Fabric or Similar Article, of which the following is a specification, reference being had to the accompanying drawing, forming a part thereof.

The figure of the drawing is a plan view of a textile fabric or similar article, showing my new design.

I claim:

The ornamental design for a textile fabric or similar article, substantially as shown.

NATHAN FEINSTEIN.
